[57] CLAIM

The ornamental design for a paper roll holder, as shown and described.

DESCRIPTION

FIG. 1 is a perspective view of the paper roll holder showing my new design;

FIG. 2 is a perspective view with cover partially open thereof;

FIG. 3 is a perspective view with cover fully open thereof;

FIG. 4 is a front elevational view thereof;

FIG. 5 is a side elevational view thereof;

FIG. 6 is a side elevational view of a second embodiment;

FIG. 7 is a perspective thereof;

FIG. 8 is a perspective view with cover fully open thereof;

FIG. 9 is a perspective view of a third embodiment;

FIG. 10 is a perspective view with cover fully open thereof;

FIG. 11 is a front elevational view thereof;

FIG. 12 is a side elevational view thereof;

FIG. 13 is a side elevational view of a fourth embodiment;

FIG. 14 is a perspective view thereof;

FIG. 15 is a perspective view with cover fully open, thereof.
